UNITED STATES PATENT OFFICE

ARCHIBALD M. FITZKEE, OF ATKINSON, ILLINOIS.

SAFETY-POCKET.

No. 811,045.

Specification of Letters Patent.

Patented Jan. 30, 1906.

Application filed September 20, 1905. Serial No. 279,275.

To all whom it may concern:

Be it known that I, ARCHIBALD M. FITZKEE, a citizen of the United States, residing at Atkinson, in the county of Henry and State of Illinois, have invented new and useful Improvements in Safety-Pockets, of which the following is a specification.

The invention relates to garment-pockets; and it consists of two spring-strips of hard rubber or steel secured to the mouth of the pocket for holding the same normally closed, whereby the contents of the pocket are prevented from falling out.

In the accompanying drawings, Figure 1 is a perspective view of one of the strips, and Fig. 2 is a similar view of the other strip. Fig. 3 is a vertical sectional view of the pocket with the invention applied. Fig. 4 is plan view of the mouth of the pocket.

Referring specifically to the drawings, 10 denotes a spring-strip of hard rubber or steel, on one side of which is secured a rubber tube 11. The strip has thread-holes 10^a for attachment. A second spring-strip of hard rubber or steel is indicated at 12, being also provided with holes 12^a for the attaching-threads. The manner in which these strips are attached to the pocket is clearly illus-

trated in Fig. 3, in which 13 denotes the garment and 14 the lining forming the pocket 15. 3c The strips are located at the mouth of the pocket and sewed under the lining 14, with the tube 11 between the strips. The strips are also sewed together at their ends.

When attached as herein described, the 35 strips hold the mouth of the pocket normally closed. A pencil or other article can be readily inserted and will be held by the strips with a yielding pressure due to the rubber tube 11, whereby the article is effectively 40 prevented from dropping out of the pocket.

Having thus described my invention, what is claimed as new, and desired to be secured by Letters Patent, is—

The combination with a pocket, of oppositely-disposed spring-strips secured to the mouth of the pocket for holding it closed, and a rubber tube secured to the face of one of said strips.

In testimony whereof I have signed my 50 name to this specification in the presence of two subscribing witnesses.

ARCHIBALD M. FITZKEE.
